Fig. 2.

Fig. 5.

Fig. 4.

A technical drawing of a double-sided metal plate. The plate is shown in two views: a front view on the left and a back view on the right. Both views show a central horizontal slot with a rectangular cutout at the bottom. The front view features diagonal hatching across the entire surface, with the number '5' at the bottom left corner. The back view also has diagonal hatching, with the number '1' at the top left corner and the number '4' at the top center. The central slot is labeled with the number '2' at the bottom right corner of the front view and the number '3' at the bottom right corner of the back view.

UNITED STATES PATENT OFFICE.

ARTHUR E. POULSTON, OF RAVENNA, OHIO.

JOINT FOR CONCRETE STRUCTURES.

1,279,431.

Specification of Letters Patent. Patented Sept. 17, 1918.

Application filed November 24, 1917. Serial No. 203,818.

To all whom it may concern:

Be it known that I, ARTHUR E. POULSTON, a citizen of the United States, residing at Ravenna, in the county of Portage and State 5 of Ohio, have invented a new and useful Joint for Concrete Structures, of which the following is a specification:

This invention relates to joints for concrete structures such as roads, sea walls, 10 retaining walls, fire walls, etc., where the concrete is exposed to climatic changes and is necessarily formed in sections, thereby to allow for expansion and contraction. Owing to the relative movement of separate concrete sections and any metal housed in and 15 connecting the same, it has not ordinarily been practical to connect separate concrete sections with metal, particularly where the concrete is exposed to severe climatic changes. 20 For example, in many localities, concrete roads, which are laid in sections, expand and contract to such an extent that one section often rises a considerable distance above the next adjoining section with the result 25 that an uneven roadway is produced which can only be repaired by chipping off the upwardly projecting portion of the concrete.

One of the objects of the present invention is to provide means whereby lengths of 30 metal can be used within the meeting ends of concrete sections thus to hold the faces of the sections flush, a novel form of expansion sleeve being provided in connection with these metal members to permit 35 said members to expand and contract independently of the concrete while, at the same time, holding the engaged sections of concrete in proper relation to each other 40 under various climatic conditions.

A still further object is to provide an 45 expansion sleeve of simple and inexpensive construction which can be applied readily to the metal rods and embedded therewith within the concrete at the time of the formation of the concrete sections, these expansion sleeves being sufficient to keep the concrete out of direct contact with the rods, thus to 50 allow for the free expansion and contraction of the rods.

With the foregoing and other objects in view which will appear as the description proceeds, the invention resides in the combination and arrangement of parts and in 55 the details of construction hereinafter de-

scribed and claimed, it being understood that changes in the precise embodiment of the invention herein disclosed, can be made within the scope of what is claimed, without departing from the spirit of the invention. 60

In the accompanying drawings the present invention has been shown applied to a road construction and the preferred form of the invention has been shown. 65

In said drawings:

Figure 1 is a plan view of a section of a road formed of concrete and showing, in dotted lines, some of the positions in which the expansion sleeves and rods can be 70 placed within the ends of the sections of the road.

Fig. 2 is a section on line 2—2 of Fig. 1, said section being on an enlarged scale.

Fig. 3 is a section on line 3—3 of Fig. 1. 75

Fig. 4 is an elevation of an expansion sleeve.

Fig. 5 is a longitudinal section through the sleeve and showing the rod therein.

Referring to the figures by characters of reference 1 designates a section of a concrete road, the ends of the section being preferably obliquely disposed as indicated, thus to permit the weight of a load to be gradually transferred from one section to the other at the joint. The ends of the sections can, if desired, be mounted on inverted T-rails as indicated at 2 in Fig. 3, which constitute efficient supports. 80

The means employed for holding the sections of concrete flush under various climatic conditions includes a metal rod 3 which can be of any desired length and of any desired cross-sectional contour. This rod is provided with a sleeve 4 formed of thin material and which is slightly longer than the rod, the ends of the sleeve being closed by caps 5 which can be made of any desired material, so that spaces are thus left between the caps and the ends of the rod 3 to allow 90 for expansion of the rod within the sleeve 4. 95

The sleeve 4 can be made of any material desired. Under ordinary conditions it is preferred to make these sleeves by wrapping the rods with waxed paper, the caps 5 being pressed out of waxed paper adapted to maintain their shape while the sleeves are being embedded within the concrete as hereinafter pointed out. The sleeves can also 100 be made of wood shavings wrapped about a 110

rod or they can be made of fabric which can be creosoted, of glass, celluloid, metal or rubber. In fact the casing can be of any material sufficient to completely surround the rod and prevent it from coming into contact with the concrete in which the sleeve or casing is embedded.

In constructing, for example, a concrete road having the present improvements combined therewith, the sections of the road are molded as ordinarily but within the ends of the sections are embedded the rods 3 with their sleeves 4 and caps 5 arranged thereon. These rods will extend into the ends of two adjoining sections and will bridge the space between the sections, as shown particularly in Fig. 3. The sleeves with the rods therein are preferably arranged with their uppermost portions approximately along a line extending transversely of the concrete road at the center thereof. The caps 5 will keep the concrete away from the ends of the rod thus leaving spaces into which the rod can expand when subjected to heat. The sleeve 4 will keep the concrete away from the rod so that the expansion and contraction of the rod will not be interfered with.

By arranging a series of these sleeves and rods at the ends of the sections as shown, for example, in Fig. 1, the said sections will be maintained at all times with their faces flush and one cannot be caused to rise or fall as a result of climatic changes, without a corresponding movement of the other. The rods

can be disposed in any manner desired in order to produce the best results.

It will be obvious that by utilizing expansion sleeves made and positioned in the manner set forth, a concrete structure will be rendered more permanent than where no such means are used or where independent expansion and contraction of metal and concrete is not permitted.

As the sleeve can be made of paper, the cost of incorporating the improvement in a concrete structure will not be objectionable and will more than offset the cost of repairs and reconstruction which is constantly necessary in order to keep the ordinary concrete structure in good condition.

What is claimed is:—

The combination with a concrete structure made up of separate sections, of a rod extending into the meeting portions of the two sections, an expansion sleeve extending around the rod for holding the rod out of contact with the concrete, said sleeve extending beyond the ends of the rod, the ends of the sleeve being closed and spaced from the rod.

In testimony that I claim the foregoing as my own, I have hereto affixed my signature in the presence of two witnesses.

ARTHUR E. POULSTON.
